UNITED STATES PATENT OFFICE.

HIRAM SNYDER, OF OWENSBOROUGH, KENTUCKY, ASSIGNOR OF ONE-THIRD
TO JOHN M. CARSON, OF SAME PLACE.

HORSESHOE-CALK.

SPECIFICATION forming part of Letters Patent No. 241,516, dated May 17, 1881.

Application filed February 12, 1881. (No model.)

To all whom it may concern:

Be it known that I, HIRAM SNYDER, a citizen of the United States, residing at Owensborough, Daviess county, and State of Kentucky, have invented certain new and useful Improvements in Toe-Calks for Horseshoes, of which the following is a full, clear, and exact description, reference being had to the accompanying drawings and the letters of reference

marked thereon, in which—

Figure 1 is a perspective view of my improved toe-calk for horseshoes. Fig. 2 is a perspective sectional view of a horseshoe with the toe-calk shown in Fig. 1 applied thereto. Fig. 3 is a perspective view of a toe-calk for horseshoes constructed substantially the same as that shown in Fig. 1, with the addition of lateral wings; and Fig. 4 is a plan view of a horseshoe turned upside down and with the toe-calk shown in Fig. 3 applied thereto.

My invention relates to an improved construction of toe-calks for horseshoes; and the object of my invention is to provide a toe-calk which shall consist of one homogeneous piece of metal so formed that it may readily be applied to a machine-made horseshoe, (which does not have a toe-calk formed upon it when put upon the market,) as well as to a hand-made horseshoe, and possess all the necessary constructions required for its permanent application to a shoe, either before or after the shoe has been nailed to a horse's hoof.

My improved toe-calk (indicated in the drawings by the letter A) is made of a single piece of metal, having a body portion, *b*, adapted to fit and have a broad bearing against the under side and front edge of the toe portion of a horseshoe, as signified in the drawings. This body portion *b* is turned down in front, so as to form the calk proper, *b'*, of the toe-calk, as shown, while at the rear of the body portion *b* a clinching or welding lap, *b²*, is provided. This lap projects upwardly, as at *b⁴*, nearly at a right angle with the body *b*, a distance equal to the ordinary thickness of the inner edge of a horseshoe, and is then turned down nearly parallel with the body portion *b*, as shown.

The lap *b²*, as clearly shown in the figures, is of a length greater than the combined width

and thickness of the shoe *B* at the point where the toe-calk is applied to the shoe, so that its end, which is beveled, as at *b³*, in order to facilitate its bending, may overlap the outer edge of the shoe and lap down upon the calk proper, *b'*, when applied to the shoe *B*, as indicated in sectional view, Fig. 2, the toe-calk thus entirely inclosing the shoe at its point of application thereon.

In applying the toe-calk *A* to the shoe *B* before it is nailed to a horse's hoof, the shoe is slid into position between the body portion *b* and lap *b²* of the toe-calk. This done, the parts may, if desired, be subjected to a welding heat and the lap *b²* turned down from its position shown in Fig. 1 to its condition shown in Fig. 2, with its beveled end *b³* lapsing upon the calk proper, *b'*, as shown.

In Fig. 3 I have shown my improved toe-calk with lateral wings *w w*, extending out from its body portion *b*. These wings serve to give additional bearing and security to the toe-calk upon the shoe, and are perforated at *n n*, to correspond with like perforations in the shoe *B*, so that when this calk has been applied to a shoe one of the nails used in fastening the shoe to the hoof of a horse will pass through a perforation, *n*, of the wings, and thus contribute to the security of the toe-calk upon the shoe.

Instead of welding the calk to the shoe and then applying the shoe to the hoof of a horse, the calk may readily be applied to a shoe already upon the horse's hoof. This is done by cutting or burning a slot in the hoof, just above the shoe, similar to the lap *b²*, so as to receive the same, and then inserting the lap through the slot from the rear of the toe-point edge of the shoe, after which the thinned end *b³* is drawn down or clinched upon the front edge of the shoe and upon the calk proper, *b'*, as shown in Fig. 2. In this manner my improved toe-calk may be applied to any ordinary shoe already nailed to a horse's hoof, thus saving the time required to remove the shoe in order to apply the calk, as well as the time to reset the shoe.

I claim—

1. In a toe-calk for horseshoes, the combination of a body portion, *b*, a calk proper, *b'*, and

a lap clinching or welding portion, b^2 , of a length sufficient to extend entirely over the toe portion of the shoe and down in front thereof, and to be welded or clinched to the calk proper, 5 b' , substantially as described.

2. The perforated wings $w w$, in combination with the welding or clinching lap b^2 , body por-

tion b , and calk proper, b' , substantially as described.

Signed in presence of two subscribing witnesses.
